TYPEWRITING MACHINE

Arthur A. Johnson, Bridgeport, Conn., assignor
to Autographic Register Company, Hoboken,
N. J., a corporation of New Jersey

Application April 16, 1931, Serial No. 530,517
Renewed August 15, 1934

29 Claims. (Cl. 197—126)

This invention relates to typewriting machines, and more particularly, to means for facilitating the making of manifold copies.

Heretofore it was suggested, in order to eliminate the use of carbon or transfer sheets or strips, or duplicating ribbons running with or extending transversely of the continuous worksheet strips on the platen, to provide a wheel or circular disk carrying at its edge a transfer medium and locating these disks between the several worksheet strips so that the transfer material extends across the line of writing and so that the disk rotates or rolls in contact with the worksheet strips at the writing line and presents its entire periphery to the writing line as the typewriter carriage travels from side to side in the writing operation.

It has also been proposed to feed the superposed worksheet strips in unison in line-feeding direction by providing the platen with pin-bearing bodies and providing the worksheet strips with longitudinally extending marginal rows of pin-wheel engaging apertures.

An object of the present invention is to provide means for carrying transfer material between the worksheet strips at the line of writing and for causing the transfer medium to enter between the adjacent worksheet strips as the writing progresses from one side of the strips to the other, and yet permit the strips to be advanced and have their feeding movements controlled by the pin-wheels and pin-wheel engaging apertures.

Another object of this invention is to provide improved means for supporting and controlling a rolling carbon carrier so that it may be easily and quickly removed from the machine to be replaced by another.

Other features and advantages will hereinafter appear.

In the accompanying drawings—

Figure 1 is a front elevation of a typewriting machine platen, showing the present invention applied thereto.

Fig. 2 is a similar view of a fragment of the platen, showing the rolling carbon holder in the position which it assumes when printing is being performed at the extreme edge of the writing zone on the worksheet strips.

Fig. 3 is a detail view showing a modification wherein the transfer medium is detachably secured to the rolling holder.

Fig. 4 is a side elevation showing the platen, type mechanism, and carriage therefor, with the

device of the present invention associated with the platen.

Fig. 5 is a plan view of the carriage for the rolling carbon holders, fragments of the wheel-supporting carriage being shown.

Fig. 6 is a transverse sectional view of the carriage taken on the line 6—6 of Fig. 5.

Fig. 7 is a bottom plan view of the carriage shown in Figs. 5 and 6.

Fig. 8 is a detail view showing the upper end 10 of a supporting frame and one of the arms on which the carriage rails are supported.

Fig. 9 is a side elevation of the means for holding the uppermost worksheet from falling forwardly.

Fig. 10 is a sectional view of the part shown in Fig. 9.

Fig. 11 is a front elevation of a modified form of this invention.

The device of the present invention may be applied to the ordinary typewriter where the platen is mounted to move step-by-step in letter feed direction, but is herein shown as applied to the kind of typewriter having a relatively non-traveling rotatable platen 10 mounted on a shaft 11 supported by arms 12. The type bars 13 may be mounted in a segment 14 supported by a carriage 15 running on rollers 16 on a supporting frame 17. The type bars 13 are provided with actuating mechanism 18 so that they swing forwardly and rearwardly against the front face of the platen at the writing line 19.

The platen 10 is provided with a paper table 20 fastened to a frame 21 rising above the main frame 17 and it is over this work-table 20 that the continuous worksheet strips 22 are led into engagement with the platen to receive impressions from the type bars 13 which are performed on the original copy or top worksheet strip 22 through an inking ribbon 23. The worksheet strips, in the form of the present invention shown herein, are provided with marginally disposed rows of apertures 24 adapted to be aligned and engage pins 25, of which there may be as many as desired, four being shown at each end of the platen 10. Of course, the pins 25 may be mounted directly on the platen, or they may be mounted on wheels secured to the platen, as desired.

For the purpose of making manifold copies on the under worksheet strips, it was previously proposed to provide a wheel or disk having a margin of transfer material around its periphery adapted to be supported between the several worksheet strips so as to be located on the line of writing 19 and to rotate, or more properly, roll 55

into the line of writing and between the superposed worksheet strips as the typewriting operation progresses from one side of the platen to the other.

5 However, with the disks or wheels heretofore proposed for this purpose, it was impossible to reach the lateral edges of the worksheet strips when the strips were fed by the pins 25, because the wheels or disks would be interfered with by 10 the pins 25, both on occasion, being located at the line of writing. This could be obviated by providing a wide enough margin at each side of the worksheet strips in which no writing is to be done. In other words, by restricting the width 15 of the writing zone so that the portions of the transfer wheels at each side of the perpendicular would not reach the pins. This, however, would entail a great loss of writing space and would be prohibitive on account of the added cost entailed 20 by the increased width of the worksheet strip which would be necessary.

This is obviated by the present invention by employing segmental carbon holders and making the arc thereof substantially equal to the line of 25 writing so that radial extending edges of the segment will be kept clear of the pins even when the arcuate portion of the segment is located on the line of writing and just inside of the row of pin-engaging apertures 24.

30 Accordingly, as shown, the present invention provides segments 26 substantially vertically disposed and having at their lower portions arcuate bands 27 of carbon paper or the like adapted to project into the spaces between the adjacent 35 worksheet strips 22 at the line of writing 19, as indicated in Fig. 1.

These segments 26 may be made of any suitable material such as pressed board or celluloid, and are pivotally mounted at their upper ends, having, for this purpose in the form shown, an aperture 28 adapted to receive a pin 29 on a carrier 30. For the purpose of permitting the segments 26 to be applied and removed with great ease 40 from the carrier 30 and yet be held securely there- 45 to for pivotal movement, the upper end of the segment is provided with a partially circular tab 31 in which the hole 28 is provided and which is adapted to be slid under arms 32 which may be, as shown in Figs. 5, 6 and 7, lanced from the 50 carrier 30, which keep the tab 31 from falling off the pin 29. The tab may be placed under the arms 32 by bending or flexing it while at the same time aligning the hole 28 over the pin 29. Or, the pin may be slipped into an elongated hole 55 33 at the upper end of the tab and may then be pushed vertically, the margins of the tab 31 sliding under the arms 32 and the center portion of the tab being flexed upwardly when the rounded top surface of the pin 29 reaches the end of the slot 33 so as to flex the tab. The upward movement is then continued until the pin 29 enters the hole 28.

When the device is to be used with a travelling platen instead of, as shown, with a travelling type basket, the carriers 30 may be mounted on any suitable supports between which the under worksheet strips 22 may be fed. In the present case, as stated, the platen 10 is mounted relatively stationary while the type basket travels, and 70 hence, according to the present invention in the form shown herein, the carriers 30 are mounted to travel with the traveling movements of the type basket carriage 15.

75 For this purpose, the upwardly extending frame 21 is provided with forwardly extending arms 34,

one on each side of the machine, and these arms have secured to them U-shaped rails 35 on each of which a carrier 30 is adapted to slide from one side of the machine to the other as the typewriting progresses. When the typing is being performed at the center of the platen, the segment 26 will be in the position shown in Fig. 1, so that its median line is centrally disposed with relation to the platen. When, however, the carrier 30 is at its extreme position to one side or the other 10 with relation to the platen as shown in Fig. 2, the radial edge 36 of the segment is perpendicular to the line of writing, and hence is clear of any interference with or by the pins 25 carried by the platen, yet the transfer strip 27 is located very 15 close to the pin-engaging apertures 24 and writing may be performed at that point as indicated in dotted lines by the type bar 13.

The uppermost worksheet strip is held against falling over forwardly by a bail 37 pivotally 20 mounted at the forward ends of the arms 34 and held in place by split washers 38 engaging trunnions 39 on the bail.

For the purpose of causing the carriers 30 to travel step-by-step in coordination with the 25 traveling movements of the type basket carriage 15, the carrier is connected by cables 40 to a lug 41 on the carriage 15 and the connection may include an eye 42 which may be adjusted to take 30 up any slack in the cable.

There is a cable 40 for each carbon carrier 30. This cable extends from the lug 41 over a roller 43, then vertically and over a roller 44 at the top of the frame 21, then forwardly over a roller 45 on the arm 34 just below the U-shaped track 35, 35 then upwardly over a roller 46 supported by the U-shaped track 35. It then has a horizontal stretch 47 extending through the track 35 to the opposite end thereof where it passes over a roller 48 and from the roller 48 it has a horizontal 40 stretch 49 extending through an eye 50 in a clamping screw 51 secured to the carrier 30. The stretch 49 continues to the other side of the track 35 where it passes over a roller 52 and from thence has a stretch 53 to the opposite side of the track 35 where it passes over a roller 54, and then backwardly, downwardly and horizontally over rollers 45, 44 and 43, similar to those first described but at the other side of the machine, and back to the lug 41. Thus as the 50 type basket carriage 15 travels from one side of the machine to the other in either letter feed or return direction, the carrier 30 for each transfer segment 26 is caused to travel in step with the carriage 15.

In so traveling back and forth, the carrier 30 shifts the pin 29 on which the transfer segment is mounted and thereby causes the segment to roll in the space between the worksheet strips being in contact therewith and to successively present various portions of its arc to the writing line.

The band 27 of carbon or other transfer material is preferably made somewhat wider than would be otherwise necessary, so that different 65 portions of the band may be presented to the line of writing when desired, so that it will last longer and will not be necessary to so frequently remove the carbon segments and substitute others. For the purpose of allowing various portions of the 70 carbon band 27 to come into play, the arms 34 carrying the rails 35 and segment carrier 30 are pivotally mounted with relation to the stationary frame 21 and hence may be raised or lowered with relation to the main frame 21 and platen 10. 75

The arms 34 may have any suitable form of mounting and preferably are provided with means permitting them to be quickly located in one of several different positions. For this purpose, the arms 34 are provided with extensions 55 having an aperture 56 through which a pin 57 may also extend through one of a plurality of apertures 58 in the main frame 21. Hence, by removing the pin 57 and shifting the arms 34 and then replacing the pin, the arms 34 may be held in any one of three different positions corresponding to three different arcuate zones on the transfer band 27.

The device may be provided with a paper table 59 for guiding the lowermost worksheet strip 22 in its upward movement and one or more of the carriers 30 may be provided with plates 60 depending therefrom for the purpose of keeping the leading edges of the worksheet strips from catching on to the carriages or rails in being fed upwardly.

If desired, and as shown in Fig. 3, the band 27 of transfer or carbon material may be detachably mounted on the segment 26 which itself may be detachably mounted upon the carrier 30, and with this arrangement, a new carbon band 27 may be substituted for the consumed one by merely being removed from the segment 26.

In the form shown, the band 27 of carbon material is provided with key-hole slots 61 to engage projections or pins 62 on the segment 26 and these key-hole slots preferably extend toward each other so that the carbon band 27 may be applied by flexing its middle portion and will be held in place by merely straightening out. Further, with this arrangement, the pins 62 will remain positively connected with the carbon band 27 in both directions of movement of the segments 26.

In Fig. 11, there is shown a modification of this invention wherein the carbon holder 26a and carbon strip 27a form almost a complete circle, but even in this case the carbon strip has its terminal portions 27b so arranged as to clear the pins 25 on the platen. In this case also the peripheral length of the carbon strip is approximately equal to the line of writing so that when the carbon strip is at each end of the platen, the cut-out 27c therein will clear the pins 25.

In the use of the device, since the arcuate transfer strip 27a is merely suspended between the worksheet strips at the line of writing, rotation of the platen in line-feed direction might tend to cause the operating portion of the carbon strip 27a to move out of the line of writing. However, when the carriage is returned, the rolling action between the carbon strip and the paper causes the strip to easily slide down again to the line of writing so as to be in proper position to start the next line. This rolling action also permits the lower edge of the carbon strip 27a to move to proper position in the line of writing, even where the worksheet strips are transversely perforated because the portions of the carbon strip which project from the holder 26a at the line of perforations is made with the edge of the carbon strip 27a at an angle to the line of perforation and, as the carbon holder 26a rolls, the strip 27a is in effect cammed over the protruding portions of the paper at the line of perforations.

Variations and modifications may be made within the scope of this invention and portions of the improvements may be used without others.

Having thus described the invention, what is

claimed as new and for which it is desired to obtain Letters Patent, is:—

1. In a typewriter, the combination of a platen for carrying a plurality of continuous worksheet strips; type mechanism movable in step-by-step letter feed or return direction relative to the platen; a transfer strip; and means travelling with the type mechanism for supporting said transfer strip between the worksheet strips at the line of writing so that successive portions of the strip progressively roll into the line of writing conjointly with the traveling movements of the type mechanism. 5

2. In a typewriter, the combination of a platen for carrying a plurality of continuous worksheet strips; type mechanism movable in step-by-step letter feed or return direction relative to the platen; a carrier movable with the type mechanism in letter feed direction; a holder rotatably mounted on the carrier; and a transfer strip on 10 the peripheral margin of the holder, said transfer strip being located between the worksheet strips at the line of writing and having successive portions progressively rolled into the line of writing conjointly with the traveling movements of the type mechanism. 15

3. In a typewriter, the combination of a platen for carrying a plurality of continuous worksheet strips; type mechanism movable in step-by-step letter feed or return direction relative to the platen; a carrier movable with the type mechanism in letter feed direction; a segmental holder rotatably mounted on the carrier; and an arcuate transfer strip on the arcuate margin of the segmental holder, said arcuate transfer strip 20 being located between the worksheet strips at the line of writing and being progressively rolled into the line of writing as a result of the traveling movements of the carrier with the type mechanism. 25

4. In a typewriter, the combination of a platen for carrying a plurality of continuous worksheet strips; said platen having feeding pins thereon 30

and the worksheet strips having marginal pin-engaging apertures; type mechanism movable into line writing position and in step-by-step letter feed and return direction relative to the platen; a transfer member; and means travelling 35 with the type mechanism supporting said transfer member between the worksheet strips at the line of writing so that successive portions progressively roll into the line of writing conjointly with the traveling movements of the type mechanism and portions of which are cut-away to avoid interference with or by the feeding pins of the platen when typing is being performed adjacent the pins of the platen and the marginally apertured edges of the worksheet strips. 40

5. In a typewriter, the combination of a cylindrical platen for carrying a plurality of continuous worksheet strips and type mechanism movable relatively in step-by-step letter feed or return direction, said platen having spaced circular rows of feeding pins and said worksheets having marginal pin-engaging apertures; an arcuate transfer strip; and means for supporting said transfer strip between the worksheet strips at the line of writing so that successive portions progressively roll into the line of writing conjointly with type mechanism traveling movements in letter feed or return direction, said arcuate transfer strip being in extent less than a complete circle and being cut-away so as to avoid inter- 45

75

- ference with or by the feeding pins of the platen when typing is being performed adjacent the pins of the platen and the marginally apertured edge of the worksheet strips.
- 5 6. In a typewriter, the combination of a platen for carrying a plurality of continuous worksheet strips and type mechanism movable relatively in step-by-step letter feed or return direction, said platen having longitudinally spaced circular rows 10 of feeding pins and said worksheets having marginal pin-engaging apertures; a transfer strip; and means for supporting said transfer strip between the worksheet strips at the line of writing so that successive portions progressively roll into 15 the line of writing conjointly with type mechanism traveling movements in letter feed or return direction, said transfer strip forming a segment of a circle and having a peripheral length approximately equal to the length of the line of writing.
- 10 7. In a typewriter, the combination of a platen for carrying a plurality of continuous worksheet strips and type mechanism movable relatively in step-by-step letter feed or return direction, said 20 platen having spaced circular rows of feeding pins and said worksheets having marginal pin-engaging apertures; a carrier; a holder rotatably mounted on the carrier; and a transfer strip forming the peripheral margin of the holder, said transfer strip being located between the worksheet strips at the line of writing and having successive portions progressively rolled into the line of writing as a result of said relative traveling movements in letter feed or return direction and having a peripheral length approximately equal to the length of the line of writing and slightly less than the distance between the spaced circular rows of feeding pins and pin-engaging apertures at opposite lateral edges of the worksheet strips.
- 25 8. In a typewriter, the combination of a platen for carrying a plurality of continuous worksheet strips and type mechanism movable relatively in step-by-step letter feed or return direction, said platen having spaced circular rows of feeding pins and said worksheets having marginal pin-engaging apertures; a carrier; a segmental holder rotatably mounted on the carrier; and a transfer strip forming the arcuate margin of the segmental holder, said transfer strip being located 30 between the worksheet strips at the line of writing and having successive portions progressively rolled into the line of writing as a result of said traveling movements in letter feed or return direction, the length of the arcuate transfer strip having a peripheral length approximately equal to the length of the line of writing and slightly less than the distance between the spaced circular rows of feeding pins and the pin-engaging apertures at opposite lateral edges of the work sheet strips.
- 35 9. In a typewriter, the combination of a platen for carrying a plurality of continuous worksheet strips and type mechanism movable relatively in step-by-step letter feed or return direction, said platen having spaced circular rows of feeding pins and said worksheets having marginal pin-engaging apertures; a carrier; a segmental holder rotatably mounted on the carrier; and a transfer strip, forming the arcuate margin of the segmental holder, said transfer strip being located 40 between the worksheet strips at the line of writing and having portions progressively rolled into the line of writing conjointly with the traveling movements of the carrier with the type mechanism, the length of the arcuate transfer strip being substantially equal to the length of the line of writing.
- 45 10. In a typewriter, the combination of a platen for carrying a plurality of continuous worksheet strips, said platen having spaced circular rows of feeding pins thereon and the worksheet strips having marginal pin-engaging apertures; type mechanism movable into line writing position and in step-by-step letter feed and return direction relative to the platen; a carrier 5 10 movable with the type mechanism in letter feed direction; a holder rotatably mounted on the carrier; and an arcuate transfer strip on the peripheral margin of the holder, said transfer strip being located between the worksheet strips at the line of writing and having portions progressively rolled into the line of writing as a result of the traveling movements of the carrier with the type mechanism, said arcuate transfer strip being in extent less than a complete circle to avoid interference with or by the feeding pins of the platen when the type mechanism carriage is in position to print near the apertured marginal edge of the worksheet strips.
- 50 11. In a typewriter, the combination of a platen; a stationary frame; a frame hinged to the stationary frame above the platen; guide rods carried by the second-named frame; carriers mounted on the guide rods; holders mounted upon the carriers; a travelling carriage movable in step-by-step feed and return directions; means connecting said carriage with the carriers to cause them to move together; members rotatably mounted one on each of said carriers and extending toward the platen; strips of transfer material one supported by each holder and having an arcuate periphery extending beyond the holder and adapted to be located on the line of writing of the platen; and means for holding said second-named frame in one of a plurality of positions, 30 35 40 said positions determining the extent to which said transfer strips extend beyond the line of writing of the platen.
- 55 12. In a typewriter, the combination of a platen; a frame above the platen; guide rods carried by the frame; carriers mounted on the guide rods; holders mounted upon the carriers; a travelling carriage movable in step-by-step feed and return directions; means connecting said carriage with the carriers to cause them to move together; members rotatably mounted on each of said carriers and extending toward the platen; and strips of transfer material supported by and having an arcuate periphery beyond each member and adapted to be located on the line of writing of the platen.
- 60 13. In a typewriter, the combination of a platen; a stationary frame; a frame hinged to the stationary frame above the platen; guide rods carried by the second-named frame; carriers mounted on the guide rods; a travelling carriage movable in step-by-step feed and return directions; a cable connecting said carriage with the carriers to cause them to move together; another cable passing through the point at which the second-named frame is hinged to the stationary frame to remain taut in all positions of the former on the latter; members rotatably mounted on each of said carriers and extending toward the platen; strips of transfer material supported by 65 70 75 and having an arcuate periphery extending beyond each member and adapted to be located on the line of writing of the platen; and means for holding said second-named frame in one of a plurality of positions, said positions determining the 75

- extent to which said transfer strips extend beyond the line of writing of the platen.
14. A carbon holder for typewriting machines comprising a segment of flexible material having 5 at its periphery and extending therebeyond an arcuate strip of transfer material approximately equal in length to the line of writing of a platen and work sheets with which it is to be used, said segment having at its apex a bearing aperture on 10 which it is mounted, and said arcuate strip being detachably mounted on the segment.
15. A carbon holder for typewriting machines comprising a segment of flexible material having at its periphery and extending therebeyond an 15 arcuate strip of transfer material approximately equal in length to the line of writing of a platen and work sheets with which it is to be used.
16. In a typewriting machine, a carrier having a pin and a pair of fingers spaced from the pin 20 and projecting toward the pin from opposite sides; and a segmental carbon holder having an aperture to receive the pin and portions adjacent the aperture adapted to underlie said fingers when supported on said pin, said fingers being adapted 25 to hold the segmental carbon holder on the pin and the portion of the carbon holder having the aperture being flexible so as to be slidable under the fingers when being placed on the pin.
17. In a typewriting machine, a carrier having 30 a pin and a pair of fingers spaced from the pin and projecting toward the pin from opposite sides; and a segmental carbon holder having an aperture to receive the pin and portions adjacent the aperture adapted to underlie said fingers when supported on said pin, said fingers being adapted 35 to hold the segmental carbon holder on the pin.
18. In a typewriting machine, a carrier having a pin and a pair of fingers spaced from the pin 40 and projecting toward the pin from opposite sides; and a segmental carbon holder having an aperture to receive the pin and portions adjacent the aperture adapted to underlie said fingers when supported on said pin, said fingers being adapted 45 to hold the segmental carbon holder on the pin, the portion of the carbon holder having the aperture being flexible so as to be slidable under the fingers when being placed on the pin and having another aperture into which the pin may extend while being flexed.
19. In a typewriting machine, a platen; a type 50 mechanism; mechanism to effect relative movement between said platen and type mechanism in letter feed and return directions; a segmental transfer device having a peripheral arcuate margin equal in length to the line of the line of writing of the platen with which it is to be used; and means supporting said segmental transfer device between worksheets superposed on the platen for oscillation about an axis above the printing point 55 of the type mechanism so that the peripheral margin of the segment will roll between said worksheets in the line of writing thereof during the letter space relative movement between the platen and the type mechanism as a result of the tractive engagement of the peripheral margin of the segment with the position of the worksheets at or adjacent the line of writing.
20. A carbon holder for typewriting machines 60 comprising a segment of flexible material; an arcuate strip of transfer material adapted to be mounted on the segment at its periphery and extending therebeyond, said arcuate strip being approximately equal in length to the line of writing 65 of a platen and worksheets with which it is to be used; and means for interchangeably connecting the arcuate strip of transfer material to the segment.
21. A carbon holder for typewriting machines comprising a segment; an arcuate strip of transfer material adapted to be mounted on the segment at its periphery and extending therebeyond, said arcuate strip being approximately equal in length to the line of writing of a platen and worksheets with which it is to be used; and means for 10 interchangeably connecting the arcuate strip of transfer material to the segment.
22. A carbon holder for typewriting machines comprising a segment; an arcuate strip of transfer material adapted to be mounted on the segment at its periphery and extending therebeyond, 15 said arcuate strip being approximately equal in length to the line of writing of a platen and worksheets with which it is to be used; and a pin and slot connection for interchangeably connecting 20 the arcuate strip of transfer material to the segment.
23. A carbon holder for typewriting machines comprising a segment having at its periphery and extending therebeyond an arcuate strip of transfer material approximately equal in length to the line of writing of a platen and worksheets 25 with which it is to be used.
24. A transfer member for typewriting machines comprising a segment of transfer material 30 having a bearing portion for connection to the typewriting machine, the periphery of said segment being approximately equal in length to the line of writing of a platen and worksheet with which it is to be used.
25. In a typewriter, a platen for supporting paper; a platen carriage; a support on the carriage; a segmental holder pivotally mounted on said support; an arcuate transfer member adapted to 35 be supported coextensively upon the periphery of the segmental holder approximately equal in length to the line of writing of a platen and worksheets with which it is to be used; and means for interchangeably connecting said transfer member on the segmental holder.
26. In a typewriter, a platen for supporting paper; a platen carriage; a support on the carriage; and a segmental transfer member pivotally mounted on the support, and at its outer peripheral edge being of a length equaling the width 40 of the writing portions of the paper and the platen.
27. In a typewriter, a platen for supporting paper; a platen carriage; a support on the carriage; a segmental transfer member pivotally mounted 45 on the support, and at its outer peripheral edge being of a length equaling the width of the writing portions of the paper and the platen; a type mechanism adapted to travel step-by-step relative to the platen; and means connecting the transfer member support to the type mechanism to move successive portions of the segmental transfer member into line writing position between the papers on the platen.
28. In a typewriting machine, a carrier having 55 a pin and a pair of fingers spaced from the pin and projecting toward the pin from opposite sides; and a segmental transfer member having an aperture to receive the pin and portions adjacent the aperture adapted to underlie said fingers when supported on said pin, said fingers being adapted to hold the segmental transfer member on the pin.
29. In a typewriting machine, a carrier hav-

ing a pin and a pair of fingers spaced from the pin and projecting toward the pin from opposite sides; and a segmental transfer member having an aperture to receive the pin and portions adjacent the aperture adapted to underlie said fingers when supported on said pin, said fingers be-

ing adapted to hold the segmental transfer member on the pin, and the portion of the transfer member having the aperture being flexible so as to be slid able under the fingers when placed on the pin.

ARTHUR A. JOHNSON.
